WALL PLAQUE

Philip A. Riley, Dayton, Ohio

Application July 9, 1949, Serial No. 3,813

Term of patent 14 years

(Cl. D29—23)

To all whom it may concern:

Be it known that I, Philip A. Riley, a citizen of the United States, residing at Dayton, in the county of Montgomery and State of Ohio, have invented a new, original, and ornamental Design for a Wall Plaque, of which the following is a specification, reference being had to the accompanying drawing, forming a part thereof, wherein the figure is a front perspective view of a wall plaque showing my new design.

The essential features of my design reside in the portions shown in full lines.

I claim:

The ornamental design for a wall plaque, as shown and described.

PHILIP A. RILEY.
